UNITED STATES PATENT OFFICE.

GEORGE C. FERGUSON, OF FREDERICTON, NEW BRUNSWICK, CANADA.

WRENCH.

1,055,971.

Specification of Letters Patent. Patented Mar. 11, 1913.

Application filed August 28, 1911. Serial No. 646,425.

To all whom it may concern:

Be it known that I, GEORGE C. FERGUSON, a subject of the King of Great Britain, residing at Fredericton, New Brunswick, 5 Canada, have invented certain new and useful Improvements in Wrenches, of which the following is a specification, reference being had therein to the accompanying drawing.

This invention relates to improvements 10 in wrenches and has for its primary object the provision of a tool simple but strong in construction and capable of ready adjustment.

The invention has for an object the provision 15 of an adjustable wrench provided with jaws opening lengthwise of the shank or handle as distinguished from the ordinary jaws at right angles to the shank.

A further object of the invention is to 20 provide a wrench wherein an adjustable jaw may be freed from its connection with an opposing jaw so as to be easily slipped bodily from one position of adjustment to another position of adjustment without requiring 25 the manipulation of screws, etc.

A still further object of the invention is the provision of adjustably related jaws wherein the means for securing the movable jaw in its desired position also constitutes 30 in part a pivot for the opposing jaw, reducing to that extent the provision of unnecessary parts, while preserving practical efficiency.

The foregoing and other features of the 35 invention will be apparent from the detailed description hereinafter contained, when read in connection with the accompanying drawings forming part hereof and wherein I have for the sake of illustration shown the preferred embodiment of the 40 invention, it being obvious that changes may be made in the device disclosed without departing from the spirit of the invention.

In the drawings, Figure 1 is an elevation 45 of the complete tool; Fig. 2 is a similar view partly in section and with the side plate removed; and Fig. 3 is an edge view.

Referring more specifically to the drawings wherein like reference characters designate 50 corresponding parts in the several views, A represents the shank or handle of the wrench, having an enlarged extension α at its forward end of substantial thickness formed with suitable pockets and 55 openings as and for purposes hereinafter pointed out.

To the extreme end of the portion α of

the handle a jaw B is inserted and securely fastened, the opposing jaw being represented at C, the latter being formed integral with 60 but offset from a stem D of angular cross section adapted to pass through and work in a channel E formed in the end portion α . The jaws B and C are disposed as shown so that they will open outwardly lengthwise 65 of the shank A, thus enabling nuts, etc., to be grasped by the extreme end of the implement which could not be reached by jaws of the right angle disposition hereinbefore discussed. 70

F represents a locking pawl having a cylindrical head f fitting a corresponding socket f' in the end portion α to constitute a pivot for the pawl, said pawl also having as shown, a series of teeth f'' across its face, 75 and the back of the pawl being flat to abut against a shoulder d' on the end portion α . The front portion of the pawl is also formed adjacent the pivot end thereof with a shoulder d^3 which is adapted to coöperate with a 80 shoulder d^4 on the under portion α to limit the forward movement of the pawl on its pivot. The face of the stem D of the jaw C is similarly toothed, as at d for coöperation with the pawl f throughout a substantial 85 range of adjustment, the stem being held in engagement with the pawl and the back of the pawl in turn against its shoulder, under normal conditions through the medium of a spring pressed plunger G engaging the 90 back of the stem D. The plunger has a tooth g at its end adapted to engage a notched portion d'' on the stem D to prevent excessive outward movement of the same. 95

To effect adjustment of the slideable jaw C the stem is forced backwardly against the pressure of the plunger G,—the latter being forced into its pocket g' ,—away from engagement with the teeth of the pawl F, the 100 pawl being prevented from following the stem D by reason of its shoulder d^3 coming into contact with the shoulder d^4 on the end portion α of the shank, as shown by dotted lines in Fig. 2, when the same may be slid 105 in the direction desired to regulate the size of the opening between the jaws. Above the pivot f of the pawl, the edge of the end portion α is formed smooth, as at α'' so that when the stem is tilted into the position 110 shown by the dotted lines referred to no tooth or obstruction is there exposed to catch on the teeth of the stem D which might interfere with the easy adjustment of the parts.

From the construction above described, it will be noted that shoulders are provided which limit the pivotal movement of the pawl in both directions, the rear edge of the pawl being held against one of the shoulders when the jaw is in its locked position by means of the yieldable member G, and the other shoulder serving to limit the outward movement of the pawl so that the teeth thereof cannot remain in engagement with the teeth of the movable jaw when it is moved to a position to permit longitudinal adjustment thereof. This construction enables the adjustment to be made by manipulating the stem only of the movable jaw, which renders it possible for any one using the wrench to readily and easily adjust the same with one hand. Furthermore, the limiting of the pivotal movement of the pawl in this manner, and the provision of the smooth edge just above the pawl prevents any possibility of the teeth of the pawl engaging the teeth of the stem of the movable jaw, during the adjustment of said jaw.

In operation, after the movable jaw C has been adjusted as desired and the wrench applied, the shank may rock the jaw B upon the pivot f of the pawl F. In this particular the pivot for the pawl also constitutes the pivot for the jaw B as the jaws are rocked into closer biting engagement with an object, while at the same time the pawl F will securely hold the jaw C in its predetermined position of adjustment until released by the positive shifting of the stem D away from the teeth of the pawl, as hereinabove outlined.

H represents a side plate adapted to cover and protect the interior working parts of the device, the plate being contoured to overlie the enlarged end portion a of the handle A and secured thereto by means of screws or equivalent fastenings h.

From the foregoing it will be appreciated that in a simple and practical way I provide a wrench possessing the requisite strength and capable of a wide range of adjustment while eliminating the relatively complicated details or parts usually employed in devices of this character.

I claim:

1. A wrench of the character described comprising a handle portion, a jaw at the end thereof, a coöperating jaw, means for adjusting said coöperating jaw including a toothed stem, a pawl adapted to engage the same, and yieldable means for forcing the shank into engagement with the pawl, the stem of the adjustable jaw and the said yieldable means having coöperating projections limiting the outward movement of the adjustable jaw.

2. A wrench of the character described

comprising a handle portion, a jaw at the end thereof, a coöperating jaw, means for adjusting said coöperating jaw including a toothed stem, a pawl adapted to engage the same, and yieldable means for forcing the shank into engagement with the pawl, the pawl being pivoted to the first mentioned jaw to permit the latter to pivot relative to the second mentioned jaw, the stem of the adjustable jaw and the said yieldable means having coöperating projections limiting the outward movement of the adjustable jaw. 75

3. A wrench of the character described, comprising a handle portion, a jaw at the end thereof, a coöperating jaw, and means for adjusting said coöperating jaw including a toothed stem, a pivoted pawl adapted to engage the same, a stop for limiting the pivotal movement of said pawl away from said toothed stem, yieldable means directly engaging the toothed stem for forcing the same into engagement with the pawl, and 85 a stop for limiting the movement of said pawl toward said toothed stem, the first mentioned jaw above the pawl having a smooth edge to permit adjustment of the adjustable 90 jaw when rocked forwardly at its upper end as the lower end of the toothed stem moves out of engagement with the pawl.

4. A wrench of the character described, comprising a handle portion, provided with 95 a jaw at the end thereof and with a transverse opening therein, a coöperating jaw loosely mounted in the opening in the handle portion, said coöperating jaw being provided with a toothed stem, a pawl pivoted 100 to the handle portion and adapted to engage the toothed stem of the coöperating jaw, a stop for limiting the pivotal movement of said pawl away from said toothed stem, yieldable means engaging the toothed stem, 105 for forcing the same into engagement with the pawl, and the pawl into engagement with said stop, the pawl being pivoted to the first mentioned jaw to permit the latter to pivot relative to the second mentioned jaw, 110 a stop for limiting the movement of the pawl toward said toothed stem whereby the toothed stem may be moved out of engagement with the pawl, the first mentioned jaw above the pawl having a smooth edge to permit adjustment of the adjustable jaw when rocked forwardly at its upper end as the lower end of the stem moves out of engagement with the pawl.

In testimony whereof I affix my signature 120 in presence of two witnesses.

GEORGE C. FERGUSON.
